UNITED STATES PATENT OFFICE.

HARRY PARROCK, OF YOUNGSTOWN, AND WILLIS McKEE, OF ELYRIA,
OHIO; SAID PARROCK ASSIGNOR TO SAID McKEE.

CONTINUOUS HEATING-FURNACE.

No. 846,506.

Specification of Letters Patent.

Patented March 12, 1907.

Application filed July 25, 1904. Serial No. 217,941

To all whom it may concern:

Be it known that we, HARRY PARROCK, of Youngstown, Mahoning county, Ohio, and WILLIS McKEE, of Elyria, Lorain county, Ohio, have invented a new and useful Continuous Heating-Furnace, of which the following is a full, clear, and exact description, reference being had to the accompanying drawings, forming part of this specification, in which—

Figure 1 is a longitudinal vertical section showing one form of our improved furnace. Fig. 2 is a horizontal section of the same, partly broken away. Fig. 3 is a cross-section on the line III III of Fig. 1 looking toward the left; and Fig. 4 is a view similar to Fig. 1, showing a modified form.

Our invention relates to the class of continuous heating-furnaces where a row of metal billets or blooms is pushed through a long furnace of tunnel form.

The object of the invention is to provide a simple and efficient construction in which the flame and gases may be conveniently distributed and the exit-ports therefore not closed at any time by the entering billets or metal pieces.

It is further designed to provide for a simple and efficient feed-out arrangement, to thoroughly mix the air and gas, to reduce the number of valves, and provide for heating the air where desired.

In the drawing, referring to the form of Figs. 1, 2, and 3, 2 represents the hearth portion, and 3 the longitudinal piers, of a continuous heating-furnace 4. The longitudinal piers extend from the transverse outlet-flue 5 to the hearth and are preferably cut through transversely at several points to allow the flame and gases to circulate more easily and thoroughly in the heating-chamber. The piers 3, between the cross-arch 6 and the port 5, are preferably cut through to or nearly to the line of the furnace-floor, while the piers 3', which extend continuously to the hearth, are only partially cut through, the recesses extending only a fraction of their depth.

The roof of the furnace has at an intermediate point a vertical cross-arch 6, the portion of the roof between said arch and the combustion-chamber being higher than the portion between the arch and the billet-receiving end of the furnace. The cross-arch

6 has a cleaning door or doors extending through it at a downward inclination and closed by a cover 14. The cross-arch is important because it provides a high space at the combustion-chamber, is strong and durable, and by suddenly reducing the space for passage of the gases it affords a more efficient heating action for the billets.

As scale is liable to drop from the billets or pieces before reaching the hearth, we preferably form the furnace-bottom between the piers with opposite inclines 7 and 8, as shown in Fig. 1, these inclines extending longitudinally of the furnace-chamber. Between the inner lower portions of these inclines the floor is preferably provided with holes 9, which lead downward completely through the furnace-bottom and into the open space 10 below the bottom. The furnace-bottom may be supported upon the transverse I-beams 10', as shown, 11 being the tie-rods connecting the buckstaves 12 on opposite sides of the furnace. The space below the furnace-bottom is open at the sides throughout the distance from the flue 5 to the port 13, through which the billets drop. The holes 9 may be normally closed by suitable doors. By removing the covers 14 and inserting a suitable pusher or rake through the holes in the arch 6 the scale may be moved along the opposite inclines and caused to drop through the holes 9 upon the floor below the furnace-bottom.

The water-cooled pipes 15 extend along the longitudinal piers, the billets or metal pieces sliding over these bars. At their inner ends the bars are extended downwardly through the hearth, as shown at 16, their parts below the furnace-bottom being led out laterally for suitable water connections.

The hearth may be formed of any desirable material, and between it and the fuel-ports is the port or slot 13, through which the billets drop. This port is preferably arranged as shown with an angular portion which shifts the direction of the drop of the billets, the lower inclined part 17 being preferably lined with metal plates 17' and provided with a loose hanging door 18, which may close the opening as it hangs in vertical position and is pushed back by the dropping piece. This inclined portion is above a transverse rest or support 19, which is merely a platform extending below the feed-out opening. On

this platform lies a forked pusher 20, which is connected to a hydraulic cylinder 21, the billet or piece dropping between the legs of the fork. After the billet has thus dropped 5 the forked pusher is moved endwise and the billet pushed out upon a suitable conveyer at one side of the furnace.

As the billets are pushed in through the opening 22 they are liable to shut off or choke 10 the entrance to the outlet-port 5 for the gases. In order to overcome this trouble, we arrange this port 5 across the furnace, preferably widen it at the top, and extend it 15 endwise to form the offset portions 23 at opposite ends. These portions 23 extend into the side walls and form extensions of the port which leads down into the double-surface regenerator 24. As the ends of the offtake-port extend beyond the length of the billet, 20 the gases are always given free exit beyond the billet ends, thus preventing choking of the gases and improper working of the furnace. The regenerator 24 may be of the ordinary double-surface type, the products 25 flowing to the left in Fig. 1 and passing out through flue 25, while the air which enters through pipe 26 and flows in sheets between the bricks 27 passes through the flues 28 and around to the flue 29. The gas enters 30 through the flue 30 and passes through valved openings 31 into the flues 32, whence it rises through the divided checker-work chamber 33 and unites with the hot air in the chamber 34, the products thence flowing 35 through the length of the furnace to the offtake-flue.

The furnace is operated in the usual manner, the line of billets lying on the water-cooled bars and being pushed in through 40 port 22. At the inner end of the hearth the billets drop from the feed-out opening onto the support below the furnace-bottom and are pushed endwise by the forked pusher and drop on a suitable conveyer.

45 In Fig. 4 we show a form similar to that of the first figures, similar parts being designated by similar numerals, except that no regenerator is employed and the heat is supplied from a coal-fired furnace 35. The construction is otherwise similar to the first form.

50 The advantages of our invention result from the offset portions of the offtake-flue projecting beyond the ends of the billets or metal pieces, also from the arrangement of the longitudinal scale-cavities between the longitudinal piers and the roof-holes for pushing the scale through the bottom holes between the longitudinal piers, also from the 55 arrangement of the forked pusher and feed-out opening, the whole giving a simple, strong, and efficient construction.

60 Variations may be made in the form and arrangement of the parts without departing from our invention.

We claim—

1. A continuous heating-furnace having a hearth at one end and an intake at the other end, spaced piers extending longitudinally between the intake and hearth, the floor of the furnace between the piers being provided with scale-pockets having discharge-openings leading downwardly through the bottoms of the pockets, the roof of the furnace having openings disposed to give access 70 therethrough to the respective pockets for forcing scale through the discharge-openings substantially as described.

2. A continuous furnace having a combustion-chamber at one end and an intake at the other end, the roof portion adjacent the combustion-chamber being elevated above the front roof portion, a cross-arch closing the space between the two roof portions, the floor of the furnace having a scale-pocket beneath the elevated roof portion and provided with a discharge-opening, the cross-arch having an opening disposed to give access 80 therethrough to the scale-pocket for forcing scale through the discharge-opening substantially as described.

3. A continuous heating-furnace having a hearth at one end and an intake at the other end, the roof portion of the furnace over the hearth being elevated above the front roof 90 portion, a cross-arch closing the space between the two roof portions, longitudinal piers supported upon the floor of the furnace and leading to the hearth, scale-pockets in the furnace-floor between the piers and beneath the elevated roof portion, said pockets having discharge-openings leading downwardly through their bottoms, the cross-arch having openings disposed to give access 100 therethrough to the respective pockets for forcing scale through the discharge-openings substantially as described.

4. A continuous heating-furnace having a feed-out opening through its floor, a billet-support below the opening, and a reciprocating pusher working across said support; substantially as described.

5. A continuous heating-furnace having a feed-out opening through its floor and inclined to the vertical, said opening leading 115 downwardly toward the intake of the furnace, and a vertically-disposed swinging door mounted within and normally closing said opening substantially as described.

6. A continuous heating-furnace having 120 a feed-out opening leading downwardly through its floor, a stationary billet-support located below the opening in position to receive the billets when they pass through said opening, and means working across the top of the support to move the billet along said support substantially as described.

7. A continuous heating-furnace having a feed-out opening leading downwardly through its floor, a billet-support below the 130

opening in position to receive billets passing therethrough, said support being disposed transversely of the furnace, the side walls of the furnace having openings at opposite ends 5 of the support, and means working through one of the openings to push billets across the support and discharge them through the opposite opening substantially as described.

8. A continuous heating-furnace having 10 a feed-out opening inclined downwardly through its floor and toward the intake of the furnace, a normally vertical swinging door mounted within and closing the feed-out opening, a billet-support located below the 15 opening in position to receive billets discharging therethrough, and means working across the top of the support to move billets thereacross substantially as described.

9. A continuous heating-furnace having 20 an intake extending the full width of the furnace, an upright outlet-flue at the intake end of the furnace intersecting the intake-pas-

sage and extending at opposite sides thereof for a vertical distance above the bottom of the passage exceeding the thickness of a bil- 25 let substantially as described.

10. A continuous heating-furnace having an intake extending the full width of the furnace, an outlet-flue at the intake end of the furnace intersecting the bottom of the intake- 30 passage and extending at opposite sides thereof throughout the height of the intake-passage substantially as described.

In testimony whereof we have hereunto set our hands.
